UNITED STATES PATENT OFFICE.

ARTHUR J. RAY, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SUBSTATION TELEPHONE CIRCUITS.

Application filed June 22, 1922. Serial No. 570,229.

The present invention relates to substation telephone circuits for automatic telephone systems, and the object of the invention is to provide a new and improved circuit arrangement for an automatic telephone substation, whereby an existing manual telephone having the usual three spring switch hook combination for closing the talking circuits can be changed into an automatic telephone by the addition of a calling device having the usual three spring shunt spring combination without adding switch hook springs.

A manual telephone changed as above mentioned has the characteristic that a subscriber who has such a telephone may operate the switches at the exchange by turning his calling device even though the receiver is on the hook. This is due to the fact that the shunt springs of the calling device, upon closing when the calling device is moved from its normal position, close a direct current bridge across the two line conductors in series with the bell. Then, as the calling device returns to its normal position, the bridge across the line conductors is interrupted a number of times. In prior circuits of this general type, the tapping of the bell is depended upon to warn the subscriber that he is doing something that he should not do. However, when a harmonic bell, adjusted to respond only to a particular frequency of ringing current, is used, no tapping occurs when the calling device is turned on account of the fact that the interruptions do not recur at the frequency for which the bell is adjusted. Consequently, a subscriber, knowing that the receiver must be removed before a call can be made, may unthinkingly cause needless operation of the exchange switches by turning the calling device with the receiver on the hook, without at all suspecting that the switches are responding. Accordingly, it is an object of the invention to provide means independent of the bell for apprising the subscriber that he is doing something he should not do when he turns the calling device while the receiver is on the hook. This object is accomplished by suitably changing the substation circuit so that current flows through the receiver in series with the bell when the calling device is moved from its normal position while the receiver is on the hook and loud clicks are heard in the re-

ceiver. The improved circuit will now be explained with reference to the accompanying drawing.

With the receiver R on the hook, the bell B is bridged across the line conductors 2 and 3 in series with switch hook contacts 9 and the condenser C. When the receiver is removed, the bell B is disconnected at contacts 9 and a direct current bridge is closed across the line conductors 2 and 3 including the upper winding of the induction coil I, right hand switch hook contact, the switch hook, transmitter T, and impulse springs 4 and 5 of the calling device CD. Also the receiver R, in series with the condenser C and the lower winding of the induction coil I, is bridged around the transmitter T.

When the calling subscriber turns the calling device CD from its normal position, shunt springs 6, 7, and 8 make contact with each other. Springs 7 and 8 shunt the transmitter T so as to afford a better dialing circuit for the automatic switches, and springs 6 and 7 shunt the lower winding of the induction coil I so as to prevent the current induced in this winding from causing disagreeable clicks in the receiver. As the calling device CD returns to normal position, the bridge across the line conductors is opened the desired number of times at impulse springs 4 and 5.

Assuming now that the receiver is on the switch hook and that the subscriber turns the calling device CD, a circuit is closed from line conductor 2 by way of the bell B, contacts 9, receiver R, shunt springs 6, 7, and 8, and calling device springs 4 and 5 to line conductor 3. As the calling device returns to normal, springs 4 and 5 interrupt the bridge across conductors 2 and 3 in the usual manner. These interruptions, not only operate the automatic switches in the exchange, but also cause a corresponding number of loud clicks in the receiver R. These clicks inform the subscriber that he is causing unnecessary operation of the automatic switches. When the calling device reaches normal position, shunt springs 6, 7, and 8 separate and open the bridge across conductors 2 and 3, whereupon the automatic switches release in the usual manner.

What is claimed is:

1. In a substation telephone circuit, a transmitter, a receiver, three switch hook

contacts adapted to close together when said receiver is lifted, two line conductors terminating, respectively, in two of said switch hook contacts, an induction coil having two windings, a calling device having a pair of control contacts and three shunt contacts, said calling device having a normal position, said shunt springs adapted to make contact with each other when said calling device is turned from its normal position, one winding of said induction coil connected in series with one line conductor, said control contacts and said transmitter connected in series in the other line conductor, a bell and a condenser connected in series, the free terminal of said condenser connected to one of said line conductors, the free terminal of said bell so connected as to afford a direct current path to the exchange from the last named free terminal, a third conductor connected at one end to the junction of said bell and condenser and at the other end to the third of said switch hook contacts, the other winding of said induction coil and said receiver connected in series in said third conductor in the order named counting from the switch hook contact end of said third conductor, and circuit connections such that said other winding and said transmitter are shunted by said shunt contacts when said calling device is turned from its normal position.

2. In a substation telephone circuit, a transmitter, a receiver, three switch hook contacts adapted to close together when said receiver is lifted, two line conductors terminating, respectively, in two of said switch hook contacts, a calling device having a pair of control contacts and three shunt contacts, said calling device having a normal position, said shunt contacts adapted to make contact with each other when said calling device is turned from its normal position, an induction coil having one winding connected in series with one line conductor, said control contacts and said transmitter connected in series in the other line conductor, a bell and a condenser connected in series across said conductors, a connection from one terminal of said receiver to the junction of said bell and condenser, a connection including the other winding of said induction coil and extending from the other terminal of said receiver to the third of said switch hook contacts, and circuit connections such that said other winding and said transmitter are shunted when said shunt contacts close together.

3. In a substation telephone for automatic telephone systems, speech transmitting and receiving means including a transmitter and a receiver, a calling device for controlling the exchange switches, switch hook contacts for closing the talking and switch control circuits, calling device contacts for bridging

the receiver across the line independent of said hook contacts and circuit connections controlled by said hook contacts for shunting the receiver when the same is removed from the hook, whereby the receiver is caused to respond to impulses only in case the calling device is operated while the said receiver is on the hook. 70

4. In a substation telephone for automatic telephone systems, a receiver for responding to incoming voice currents, a switch hook, a calling device, contacts controlled by said calling device for bridging said receiver across the line, and contacts controlled by said switch hook for shunting said receiver, whereby said calling device is adapted to control the exchange switches when the receiver is off said hook without affecting said receiver, while if the calling device is operated when the receiver is on the hook a noise is produced in said receiver to warn the subscriber. 75 80 85

5. In a substation telephone circuit, an induction coil, a transmitter, a receiver, a calling device having a pair of impulse springs, a bridge across the two line conductors including in the order named the primary winding of said coil, the said transmitter and the said impulse springs, a connection from one side of the secondary winding of said coil to the junction of said primary winding and transmitter, a connection from the other side of said secondary winding to the junction of the transmitter and said impulse springs, said second connection 90 including said receiver and a condenser, three shunt springs closed together responsive to the actuation of said calling device, and shunt circuits closed by said shunt springs for removing the transmitter resistance from the bridge and for preventing noises in said receiver during the operation of said device. 95 100 105

6. In a substation telephone circuit, an induction coil, a transmitter, a receiver, a calling device having a pair of impulse springs, a bridge across the two line conductors including in the order named the primary winding of said coil, the said transmitter and the said impulse springs, a connection from one side of the secondary winding of said coil to the junction of said primary winding and transmitter, a connection from the other side of said secondary winding to the junction of the transmitter and said impulse springs, said second connection 110 including said receiver and a condenser and three contact springs closed together by the actuation of said calling device for shunting said receiver and said transmitter. 115 120 125

7. In a substation telephone for automatic telephone systems, a voice current receiver, a calling device, contacts on said device for sending current impulses over the line when said receiver is on the hook and also while 130

it is off the hook, and shunt springs controlled by said calling device for rendering said receiver unresponsive to said impulses only when said receiver is off the hook.

5 8. In a substation telephone for automatic telephone systems, a voice current receiver, a calling device, contacts controlled by said device for sending current impulses over the associated line in series with said receiver, shunt contacts for rendering said receiver unresponsive to said impulses, and contacts operated upon the placing of said receiver on its hook for rendering said shunt contacts ineffective.

15 9. In a substation telephone circuit, a transmitter, a condenser and a receiver, a hook switch comprising contacts arranged to close and contacts arranged to open when said receiver is lifted, two line conductors 20 terminating respectively in two of said hook switch contacts, a calling device comprising normally open shunt contacts and normally closed interrupter contacts, the latter in series with one of said line conductors, an induction coil having two windings one of 25 which is in series with the other of said line conductors, a receiver bridge including said condenser, receiver and second winding

of said induction coil, that bridge being closed through the third of said hook switch 30 contacts, said circuit arrangement preventing the flow of direct current through said receiver when said hook switch is operated and causing the flow of direct current through said receiver if said calling device 35 is moved off-normal before the hook switch is operated.

10. In a telephone substation, a transmitter, a receiver, a condenser, a ringer and an induction coil, a line circuit containing said 40 transmitter and one winding of said induction coil in series, there being normally a circuit bridged across said line including said condenser and said ringer but excluding said induction coil, and means comprising 45 hook switch springs for opening the circuit of said ringer and for closing a shunt circuit for said transmitter, said shunt circuit comprising said condenser, receiver and the second winding of said induction coil, 50 said condenser preventing the flow of direct current through said receiver.

In witness whereof, I hereunto subscribe my name this 19th day of June, A. D., 1922.

ARTHUR J. RAY.
